US0D1020972S

(12) **United States Design Patent** (10) Patent No.: **US D1,020,972 S**
Meissen et al. (45) Date of Patent: ** Apr. 2, 2024

(54) **RETICLE**

- (71) Applicant: **Crimson Trace Corporation**, Columbia, MO (US)
- (72) Inventors: **Tim Meissen**, Columbia, MO (US); **Michael Lindsay**, Columbia, MO (US); **Michael Cottrell**, Ashland, MO (US); **John Oller**, Columbia, MO (US)
- (73) Assignee: **Crimson Trace Corporation**, Columbia, MO (US)
- (**) Term: **15 Years**
- (21) Appl. No.: **29/792,974**
- (22) Filed: **May 3, 2022**

Related U.S. Application Data

- (63) Continuation-in-part of application No. 29/790,817, filed on Dec. 16, 2021.
